UNITED STATES PATENT OFFICE.

WILLIAM JONES, OF LURGAN, IRELAND.

DESIGN FOR A BOX.

No. 38,468.

Specification for Design.

Patented Feb. 26, 1907.

Application filed December 31, 1906. Serial No. 350,308. Term of patent 3½ years.

To all whom it may concern:

Be it known that I, WILLIAM JONES, a subject of the King of Great Britain, and residing at Lurgan, Ireland, and doing business at No. 82 Franklin street, in the city of New York, borough of Manhattan, in the county and State of New York, have invented a new, original, and ornamental Design for Boxes, reference being had to the accompanying drawing, the figure being a plan view of a box showing my new design.

What I claim is—

The ornamental design for a box, as shown.

WILLIAM JONES.
